SPARK PLUG

Frank A. Sharpnack, Chicago, Ill., assignor of
one-half to Byron A. Hathaway and William
B. Fox, both of Chicago, Ill.

Application May 29, 1930, Serial No. 457,120
Renewed August 15, 1933

2 Claims. (Cl. 123—169)

This invention relates to sparkplugs, and its object is the production of a new article of manufacture consisting in a sparkplug having its core composed of a refractory, insulating and practically unbreakable material known to the trade as Lavite, or the entire body of the plug may be of Lavite only, there being no metal therein excepting the electrodes.

It is also an object of this invention to provide a sparkplug of the nature stated and having parts of special construction and arrangement as set forth in the accompanying drawing of which Fig. 1 represents a side view of a sparkplug of the customary construction provided with a Lavite core. Fig. 2 shows a sparkplug partly in vertical section and having a removable sleeve of insulating materials surrounding the axial electrode and arranged to create a plurality of spaced recesses about that electrode. Fig. 3 shows a sparkplug with a body composed solely of refractory insulation, i. e. Lavite and having its lower part formed with spaced recesses. Fig. 4 shows a sparkplug as in Fig. 3 with the body composed solely of Lavite with the exception of the electrodes and a metal sleeve bearing the external threads. Fig. 5 illustrates a sparkplug constructed in accordance with this invention and placed in a cylinderhead, shown in section, and providing a plurality of spark gaps in the ignition circuit. Figs. 6 and 7 are lower end views of Figs. 3 and 4.

Throughout the description and drawing, the same number is used to refer to the same part.

Considering Fig. 1, the plug is of the usual construction designated 1, and it is provided with a core of refractory material 2 known to the trade as Lavite. In this invention it is held to be the right of the applicant to use any other insulating and practically unbreakable material 40 which has the same properties and to the same extent as Lavite. That is to say, the material is very difficult to break, it will not chip or burn or melt away when used as the body of a sparkplug.

45 As shown in Fig. 2 the plug 3 has a core 4 of the material specified, and a removable sleeve 5, which is of insulating material advantageously of Lavite. The arrangement of the core and sleeve and external portions of the sparkplug as set out in Fig. 2 results in a plurality of spaced recesses 6 and 7 around the axial electrode of the plug and spaced from each other. This arrangement is found by experience to maintain the plug in continuous and extended use without 55 any accumulation of carbon thereon. In the

construction set out in Fig. 2 one or more rings of asbestos packing 8 may be introduced.

In Fig. 3 which illustrates the preferred form of this invention, the body 9 is entirely of Lavite and the screw threads 10 are cut directly therein. A U-shaped electrode 11 is secured in the lower end of the body in such a manner that it will make metallic contact with the threads in a cylinder head when it is placed thereon. It will be noted in Fig. 3 that the axial electrode is 65 surrounded by a plurality of spaced recesses 12 and 13 formed in the lower end of the body 9. Lavite is a compound of substantially the following ingredients:—silica 47.40%; magnesium oxide 48.23%; lime .64%; free iron and aluminum 70 3.97%. It is not only specially resistant to heat and relatively unbreakable, but it is alone the satisfactory insulating substance found by this applicant after extended and expensive trials that will permit the formation of screw threads 75 directly in its surface, and which is sufficiently tough to keep those threads intact, practically the same as if the threads were cut in metal, when the plug is set up in the cylinder head by a wrench, and which exhibits no damage by reason of the often rough handling sparkplugs receive.

Fig. 4 sets out the same construction as Fig. 3, with the exception that there may be used on body 14 a metal sleeve 15 which bears the external necessary threads. The U-shaped electrode 16, or whatever form of electrode is used 80 may be secured in the sleeve 15.

Fig. 5 shows the all Lavite body 17 of the sparkplug screwed into a cylinder head 18. It 90 will be noted that the U-shaped electrode 19 terminates in the body opposite the openings 20. In the operation, additional sparks are provided at such openings giving to this invention the form and advantage of those sparkplug inventions 95 which have therein a plurality of spark gaps.

Figs. 6 and 7 show bottom views of the parts as illustrated in Figs. 3 and 4 and show the spaced recesses usually cylindrical in form and disposed concentrically. The plural recesses are found by 100 experience and extended trials to prevent or in some way to keep the electrodes of the sparkplug wholly free from carbon deposits.

The operation of this invention is the same as that of any sparkplug, its believed superiority or 105 improvement over those with which applicant is familiar residing in the whole Lavite body and the recessed lower portion as described.

Having now described this invention and explained its use, I claim:—

1. As a new article of manufacture, a sparkplug having a body formed of refractory insulating material, said sparkplug having electrodes carried by said body, said body having its end portion provided with external screw threads constructed and arranged to be screwed into a motor cylinder head, one of said electrodes being arranged in proximity to said external threads and exposed to the exterior.
- 5 2. As a new article of manufacture, a sparkplug

having a body formed of refractory insulating material, said sparkplug having electrodes carried by said body, said body having its end portion provided with external screw threads constructed and arranged to be screwed into a motor cylinder head, one of said electrodes being arranged in proximity to said external threads and exposed to the exterior, and the lower end of said body being formed into a plurality of spaced skirts.
